UNITED STATES PATENT OFFICE.

EMIL BEISTER, OF FORT WAYNE, INDIANA.

CONCENTRATING TABLE.

Application filed August 8, 1924. Serial No. 730,916.

The invention relates to concentrating tables of the differentially reciprocating type, and it is adapted primarily for the separation of coal from waste materials that accompany it from the mine, such as stone, sand, clay and slate, the invention being applicable to the concentration of many other materials.

The object of the invention is to provide a novel form of table that will effectively separate coal and other valuable material from waste products that accompany the same and to provide a table having a large capacity so that the concentrating operations may be carried on economically.

The table is designed especially to treat materials that are in relatively small particles, namely, such particles as will pass through a screen having three-quarter inch openings therein.

An embodiment of the invention is illustrated in the accompanying drawings in which

Figure 1 is a plan view of the deck of a table embodying the invention; Fig. 2 a cross-sectional view on line 2—2 of Fig. 1; Fig. 3 a cross-sectional view on line 3—3 of Fig. 1; Fig. 4 a cross-sectional view on line 4—4 of Fig. 1; Fig. 5 a cross-sectional view on line 5—5 of Fig. 1; Fig. 6 a cross-sectional view on line 6—6 of Fig. 1; Fig. 7 a cross-sectional view on line 7—7 of Fig. 1; Fig. 8 an exaggerated cross-sectional view on line 8—8 of Fig. 1; Fig. 9 an exaggerated cross-sectional view on line 9—9 of Fig. 1 and Fig. 10 a cross-sectional view on line 7—7 of Fig. 1 illustrating a modified form of cover on the deck.

In the drawings the deck 1 of the table only is illustrated, it being understood that the deck is suitably supported for longitudinal reciprocation and that a driving mechanism is connected at the head or motion end 2 of the deck by which the deck is differentially reciprocated longitudinally as indicated by the arrow 3 in Fig. 1. A relatively high board 4 extends along the head end 2 of the deck and another high board 5 extends along the upper or feed side 5 of the deck.

The deck in operating position is inclined transversely downwardly so that the discharge side 6 is lower than the feed side, and any point in the head end 2 is lower than the point in the edge of the opposite or discharge end 7 that is in a line drawn

through the said point in the head end and parallel to the line of motion of the deck.

The surface of the deck is a plurality of coterminous sections A, B, and C which differ in their inclinations. Section A extends along the feed side of the deck and slopes from the head end 2 toward the discharge end 7 (Fig. 2). It also slopes transversely from the feed side to its lower boundary indicated by the broken line a—b. Sections B and C slope downwardly from section A to the discharge side 6, (Figs. 5, 6), the transverse slope of section B being greater than that of either sections A or C. At the edge 65 of the discharge end 6 of the deck the slope of the section C is the same as that of the section A so that said edge is preferably straight, (Fig. 7). The sections B and C coterminate at the broken line c—d. Section B slopes upwardly from the head end 2 to the section C and the section C slopes upwardly from section B to the discharge end 7, the longitudinal slope of section C being steeper than that of the section B 70 (Fig. 4). The result of the foregoing sections is that the deck has a twisted effect, the corner A' of the deck being the highest, the corner B' being lower than the corner A', the corner C' being lower than the corner B' and the corner D' being the lowest corner of the deck. As shown in Figs. 8 and 9 a section of the deck from corner C' to corner B' indicates a concave 75 surface on the deck, and a section from corner A' to corner D' indicates a convex surface on the deck, both effects being caused by the different inclinations of the sections A, B and C.

A suitable covering is placed on the top 80 surface of the deck. This covering may be linoleum or smooth rubber 8 or a finely corrugated rubber 9. I prefer to use linoleum or smooth rubber where the materials to be treated are relatively coarse, and where 85 the materials are relatively fine I prefer to use the corrugated rubber.

A selected number of riffles 10 is secured to the deck over the cover, the riffles being parallel to each other and disposed at a 90 predetermined angle to the direction of reciprocation of the deck indicated by the arrow in Fig. 1. The forward ends of the riffles preferably terminate on a diagonal 95 line so that a smooth or unrifflled space D is 100 present between the said line and the discharge end 7 of the deck. The riffles are 110

also tapered at their forward ends. They may be of any selected height or reduce in height down the transverse slope of the deck. For most uses of the table I find a desirable arrangement of the riffles is to arrange them in groups, the riffles of each group being of a uniform height and less in height than the group above. An effective grouping of the riffles for treating coal is shown in Fig. 5 where the two uppermost riffles constitute the highest group 11, the next five riffles constitute a second group 12, the next 12 riffles constitute a third group 13 and the remaining riffles constitute a fourth group 14. As shown in Fig. 1, the diagonal arrangement of riffles on the deck is such that the forward end or terminal of each riffle is nearer to the discharge side 6 than is the rear or head end of said riffle to said side.

20 If desirable, in treating fine materials, high riffles 15 may be provided in order to form pools over certain of the riffles to facilitate the stratification of the materials on the deck in the well known manner.

25 A feed box 16 is supported on the board 5^a adjacent to the head end 2 of the deck and a dressing water launder 17 is supported on said board and extends from the feed box toward or to the discharge end 7.

30 Where the corrugated cover 9 is used it is so placed on the deck that its corrugations will be parallel to the riffles when the latter are secured to the deck, and when so arranged the surface of the deck between each 35 two riffles is corrugated, the relatively fine channels formed by the corrugations tending to assist the riffles in directing or guiding the materials caught by the riffles toward the discharge end 7. The cover 9, when 40 used, is placed over the entire upper surface of the deck so that the space D is finely corrugated and facilitates the guiding of the heavier or waste materials to the discharge end 7 of the deck.

45 Since the longitudinal inclination of the surface of the deck at the feed side thereof is less than the longitudinal inclination thereof at the discharge side, the greater proportion or bulk of the heavier particles 50 is caused to move on the section A to the discharge end 7 of the deck and the lighter particles are rapidly released from the mass and caused to discharge at the discharge side 6, the relatively steep transverse inclination 55 of the section B expediting materially the movement of the lighter particles to the side 6. Such heavier particles as reach the sections B and C meet the greater resistance of the steeper longitudinal slopes of those sections, their movement forwardly toward the discharge end 7 being retarded thereon thus facilitating the release and discharge 60 of the lighter particles at the discharge side from those sections.

65 The twisted effect of the entire surface

of the deck is most beneficial in the cleaning of coal, since it expedites materially the separation of the coal particles from the refuse or waste products and causes a rapid discharge of the heavier gangue at the upper portion of the discharge end 7, the lighter gangue being captured by the lower and steeper portions of the deck and conveyed thereon to the discharge end 7. The table, therefore has a large capacity and practically no refuse discharges over the discharge side 6 and practically no coal passes over the discharge end 7.

When fine light particles pass out onto the space D the wash water washes them down the transverse slope of that space and they move more or less down the longitudinally inclined section C and pass over the discharge side 6 rearwardly of the corner C'.

It will be noted that each of the three sections of the surface of the deck, when the table is in operating position, is twisted or warped in effect, so that the entire surface is twisted or warped. This effect may be secured by building the deck with the several inclined sections, or by constructing the table in such a flexible manner that the twisted effect is obtained by adjusting the corners of the deck as to height so as to secure the several coterminous sloping sections on its surface.

What I claim is:

1. In a coal concentrating table, a reciprocating longitudinally and transversely inclined deck, the feed side of the concentrating surface of the deck in operating position being higher than the opposite discharge side thereof, the transverse slope of the concentrating surface of the deck downwardly from the feed side to the discharge side being greater at the head end than at the discharge end thereof and the longitudinal slope of said surface upwardly from the head end to the discharge end being greater at the discharge side than at the feed side of the deck, and riffles on the deck extending from the head end toward the discharge end thereof and diagonal to the line of reciprocation of the deck, the forward ends of the riffles respectively being nearer to the discharge side of the deck than are the rear or head ends thereof.

2. In a coal concentrating table, a reciprocating longitudinally and transversely inclined deck, the feed side of the concentrating surface of the deck in operating position being higher than the opposite discharge side thereof, the transverse slope of the concentrating surface of the deck downwardly from the feed side to the discharge side being greater at the head end than at the discharge end thereof and the longitudinal slope of said surface upwardly from the head end to the discharge end being greater at the discharge side than at

- the feed side of the deck, and riffles on the deck extending from the head end toward the discharge end thereof, and decreasing in height down the transverse slope of the
- 5 deck and diagonal to the line of reciprocation of the deck, the forward ends of the riffles respectively being nearer to the discharge side of the deck than are the rear or head ends thereof.
- 10 3. In a differentially reciprocating concentrating table, a longitudinally and transversely inclined deck, the upward longitudinal slope of the concentrating surface of the deck from the head end to the discharge
- 15 end being greater at the discharge side than at the feed side thereof and the transverse slope of the said surface downwardly from the feed side to the discharge side being greater at the head end than at the dis-
- 20 charge end thereof, a corrugated cover on the deck, and riffles secured to the deck over the cover and extending from the head end toward the discharge end of the deck, the corrugations in the cover being parallel to the
- 25 the riffles the riffles being diagonal to the

line of reciprocation of the deck and having their forward ends respectively nearer to the discharge side of the table than are the head ends thereof.

4. In a differentially reciprocating coal concentrating table, a transversely inclined deck having riffles on its concentrating surface diagonal to the line of the reciprocation of the deck and extending from its head end toward the opposite discharge end and the discharge side thereof, the said concentrating surface in operating position being concave in a diagonal direction from the upper portion of the surface adjacent the head end and the feed side of the deck toward the diagonally opposite portion of said surface and said surface being convex in a diagonal direction from the upper portion of the surface adjacent the feed side and the discharge end of the deck toward the diagonally opposite portion of the said surface.

In witness whereof I have hereunto subscribed my name this 4th day of August, 1924.

EMIL DEISTER.
